CAR DOOR

Kenneth J. Tobin, Chicago, Ill., assignor, by mesne assignments, to The Youngstown Steel Door Company, Cleveland, Ohio, a corporation of Ohio

Application April 27, 1934, Serial No. 722,610

7 Claims. (Cl. 189—46)

This invention relates to sliding doors for railway cars and concerns itself more particularly with such doors constructed to receive a wooden lining.

- 5 It is an object of this invention to provide a sliding car door having a wooden lining, the structure of the door being such that the lining may readily be removed from and applied to the door while the door is mounted upon the car.
- 10 A further object is to provide a sliding car door having a wooden lining, the door being characterized by the fact that no increase in the number of fastening means utilized in the door is required for the securing of the lining and by 15 the further fact that the fastening means are disposed in the same positions in the door as in the case of a door without a lining, so that additional holes in the door are avoided.

20 A further object is to provide a door having a wooden lining, the door being so constructed that means utilized to secure the lining is incorporated with the door in such manner as to reinforce the door.

25 Other objects of the invention will become clear as the description thereof proceeds.

In the drawings forming part of this specification

Figure 1 is a fragmentary elevation of a railway house car having applied thereto a door embodying the instant invention;

Figure 2 is a vertical section taken on line 2—2 of Figure 1;

Figure 3 is a horizontal section taken on line 3—3 of Figure 1; and

35 Figure 4 is a horizontal section taken on line 4—4 of Figure 1.

40 Referring to the drawings which illustrate a preferred embodiment of the invention, the numeral 10 designates a railway house car which is provided with the customary door opening, defined along its vertical boundaries by means of front and rear door posts 11 and 12 and along its upper and lower boundaries by means of a side plate 13 and a floor 14. The opening thus defined is adapted to be controlled by means of a door 15 comprising a metallic panel 16, which may be provided with a plurality of spaced horizontal corrugations 17 and vertical corrugations 18 and 19 with which the horizontal corrugations may merge. The front and rear vertical margins of the panel are reinforced by means of the vertical reinforcing members 20 and 21 while the upper horizontal margin of the panel is reinforced by means of the member 22.

55 The door is adapted to be supported for move-

ment upon the car 10 upon a track 23 supported from a side sill 24 by means of a plurality of brackets 25. Antifrictional movement upon the track is provided for the door through the agency of hangers 26 and 27 carrying roller bearing rollers 28 disposed in rolling engagement with the track 23. The hangers 26 and 27 are provided with upwardly extending flanges 29 which are disposed in overlapping engagement with a depending flange 30 provided on the track 23 in order to avoid disengagement of the lower portion of the door from the track. At its upper margin the door is maintained upon the car and guided in its movements upon the track by means of the interengagement between a depending flange 31 provided on a retaining bar 32 secured to the depending leg 33 of the side plate 13 and the upwardly extending flange 34 provided on the horizontal reinforcing member 22. Clips 35 and 36, secured to the upper margin of the door, co-operate with the depending flange 31 of the retaining bar to prevent undue movement of the upper margin of the door toward the car.

An opening and closing arrangement, indicated in its entirety by the reference numeral 37, 25 may be utilized in conjunction with the door and a locking device, indicated as a whole by the numeral 38, may be utilized in order to fasten the door in its closed position.

The metallic door hereinabove described is designed to receive a wooden lining and for this purpose applicant's novel construction is utilized. There is, consequently, provided upon the front vertical margin of the door a member 39 preferably Z shaped in section which is secured upon the inner face of the door by means of the same rivets utilized to fasten the vertical reinforcing member 20 to said door. As clearly illustrated in Figure 3 of the drawings the member 20 is also preferably Z shaped in section, one of the longitudinally extending flanges 40 thereof being adapted to cooperate with a channel shaped formation 41 provided on the front door post 11 in order to stop the closing movement of the door and to provide a weather protection therefor. 45 Each of the members 20 and 39 are so disposed that their respective webs 42 and 43 extend inwardly and transversely of the door and, together with the disposition of the securing flanges 44 of said members, constitute a reinforcing channel for the front margin of the door, whereby said front margin is materially strengthened to resist impact between the reinforcing member 20 and the door post 11. The longitudinally extending flange 44 of the member 39 is disposed as shown 55

in Figure 3 of the drawings in parallel spaced relationship with the panel 16 of the door.

Similarly, a Z shaped member 45 is secured to the upper horizontal margin of the door by means of the rivets utilized to secure the reinforcing member 22 to said margin. The transversely and inwardly extending webs 46 and 47 of the members 22 and 45, together with the overlapping flanges of said members, provide a substantially channel shaped section for the upper margin of the door. The downwardly extending flange 48 of the Z shaped member 45 lies in spaced parallel relationship with the panel 16 of the door.

15 A Z shaped member 49 is secured upon the inner face of the panel at the lower margin thereof. The member 49 serves to reinforce the lower margin of the door and by virtue of its disposition with the web 50 thereof extending inwardly transversely of the door the upwardly extending flange 51 of said member lies in spaced parallel relationship to the panel of the door. The Z shaped members 39, 45 and 49 are so arranged upon the inner face of the metallic panel 16 that the flanges 44, 48 and 51 thereof lie in substantially the same plane.

A wooden lining 52 is adapted to be provided upon the inner face of the door 15, being maintained upon said door by the freely overlapping engagement of the flanges 44, 48 and 51 upon the front, upper and lower margins of said lining. The lining extends rearwardly beyond the door post 12 and terminates substantially with the rear edge of the panel. The reinforcing member 21 of the door, which preferably is secured to the panel by means of rivets 53 independently of said lining, may comprise an angle member one leg 54 of which extends transversely and inwardly of said panel so as to lie across the rear edge of the lining. A sealing strip 55, adapted to coact with a spark strip 56 provided on the rear door post 12, is secured to the door as by means of bolts 57, said sealing strip being disposed upon the wooden lining as clearly illustrated in Figures 1 and 4 of the drawings. The rear marginal portion of the wooden lining may be notched out as indicated at 58.

It will be readily apparent that the wooden lining 52 is securely maintained upon the inner face of the door. It will also be apparent that said lining may be removed from and a new lining applied to the door without the necessity of first removing the door from the car. If securing bolts are used to fasten both the reinforcing member 21 and the sealing strip 55 upon the door it is only necessary that these bolts be removed so as to permit removal of the members 21 and 55 and the consequent removal by sliding of the wooden lining out of engagement with the Z shaped members 39, 45 and 49. Similarly, a new lining may be replaced by sliding such new lining into engagement with said Z shaped members and subsequently bolting the reinforcing member 21 and the sealing strip 55 upon the rear margin of the door, these bolts extending through the wooden lining. However, as preferred, the reinforcing member 21 is riveted to the rear margin of the door independently of the wooden lining while the sealing strip 55 is bolted to the door by means of bolts extending through the lining. To remove a damaged lining it becomes necessary to remove the bolts 57 and the rivets 53. In the replacement of this lining it is first slidably engaged with the members 39, 45 and 49, after which the reinforcing member 21 is riveted

to the metallic panel 16. To permit such riveting of the reinforcing member 21 to the panel independently of the wooden lining said lining is notched as indicated at 58. Thereafter the sealing strip 55 is bolted to the wooden lining and the door.

It will be apparent that numerous changes and modifications in the details of the invention will be clear to those skilled in the art. It is intended, therefore, that all such modifications and changes be comprehended within this invention, which is to be limited only by the scope of the claims appended hereto.

I claim:

1. A railway car door comprising a sheet metal panel, a member secured to the front margin of said panel, said member having a flange extending transversely and inwardly of said panel and a second member secured to the inner face of said panel having a flange extending transversely and inwardly thereof and a flange disposed in spaced substantially parallel relationship to said panel, and securing means fastening said members and panel together to provide a channel shaped reinforcement for said margin of the door, said latter flange of said second mentioned member co-operating with said panel to provide a pocket for receiving one margin of a wooden lining.

2. A railway car door comprising a sheet metal panel, a Z shaped member secured to the front 30 margin of said panel upon the outside thereof, a second Z shaped member secured to said margin upon the inside of said panel, the webs of said members extending inwardly and transversely of said panel whereby said members constitute a 35 channel shaped reinforcement for said margin of the door, one flange of said second Z-shaped member being disposed in parallel relationship to said door and a wooden lining for said door, said latter flange having overlapping relationship with said lining. 40

3. In a railway house car having a door opening and a rear door post defining one boundary of said opening, a door slidably mounted upon said car for closing said opening, said door comprising a metallic panel, a wooden lining upon the inside of said panel, means secured upon the inside of said panel having overlapping engagement with the upper, lower and front margin of said lining, the rear margin of said lining extending beyond the proximate portion of said post and an angular reinforcing member having a flange secured to the rear vertical margin of said panel, the remainder of said reinforcing member lying rearwardly of a vertical plane including the rear edge of said panel. 45 50 55

4. In a railway house car having a door opening and a rear door post defining one boundary of said opening, a guard strip carried by said post, a door slidably mounted upon said car for closing said opening, said door comprising a metallic panel, a wooden lining upon the inside of said panel, means secured upon the inside of said panel having overlapping engagement with the upper, lower and front margins of said lining, the rear margin of said lining extending beyond the guard strip, a reinforcing angle secured to the rear vertical margin of said door having a flange extending across the rear edge of said lining and a sealing strip disposed upon said lining and secured to said margin of the door for cooperation with said guard strip.

5. In a railway house car having a door opening and a rear door post defining one boundary of said opening, a guard strip carried by said 75

post, a door slidably mounted upon said car for closing said opening, said door comprising a metallic panel, a wooden lining upon the inside of said panel, means secured upon the inside of said panel having overlapping engagement with the upper, lower and front margins of said lining, the rear margin of said lining extending beyond the guard strip, a reinforcing angle secured to the rear vertical margin of said door having a flange 10 extending across the rear edge of said lining and a sealing strip disposed upon said lining and secured to said margin of the door for cooperation with said guard strip, said reinforcing angle being secured to the rear vertical margin of 15 said door independently of said lining, the rear margin of said lining being notched to permit such securement, whereby said lining may be replaced while said door is mounted upon said car.

6. In a railway house car having a door opening, a guard strip secured to said car adjacent the rear vertical margin of said opening, a door 20 slidably mounted upon said car for closing said opening, said door comprising a metallic panel, a wooden lining upon the inside of said panel,

means secured upon the inside of said panel having overlapping engagement with the upper, lower and front margins of said lining, the rear margin of said lining extending beyond the guard strip, and a sealing strip seated upon the inner face of said lining and means extending through said rear margin of said lining and said sealing strip for fastening the lining and sealing strip to said panel.

7. A sliding car door comprising a sheet metal 10 panel, metallic members secured to the front and upper and lower margins of said panel upon the inside thereof, said members having webs extending at right angles to said panel whereby to dispose certain of the flanges provided on said 15 members in spaced relationship to said panel, a wooden lining for said door, marginal portions of said lining being received between said flanges and said panel and a sealing strip seated upon the remaining margin of said lining and means for 20 securing said sealing strip, said remaining margin of said lining and said panel together.

KENNETH J. TOBIN.
